UNITED STATES PATENT OFFICE.

LEONARD E. CLAWSON, OF SAN FRANCISCO, CALIFORNIA.

DEAFENING OR FILLING FOR WALLS.

SPECIFICATION forming part of Letters Patent No. 311,567, dated February 3, 1885.

Application filed April 24, 1884. (No model.)

To all whom it may concern:

Be it known that I, LEONARD E. CLAWSON, of the city and county of San Francisco, and State of California, have invented an Improvement in Deafening or Filling for Walls; and I hereby declare the following to be a full, clear, and exact description thereof.

My invention relates to a filling or deafening for walls and partitions; and it consists of a filling and a means for introducing it between the studding, as will be more fully explained by reference to the accompanying drawings, in which—

Figure 1 is a perspective view showing the mold or box. Fig. 2 is a horizontal section.

The usual manner of filling the spaces between the studding of partitions or walls for the purpose of deafening and preventing sounds from passing is by means of detached bricks or blocks of any suitable material. These blocks must be laid up by a mason or brick-layer at a considerable expense and some waste of material. Mortar is sometimes used between floors; but in such cases a supplemental permanent floor is laid, which is a conductor of sound.

My invention is designed to be applied to partitions and walls. In it I form the filling from a plastic state, molding it in the place where it is to be used, and then entirely remove the molds.

A are the vertical posts or studding of a wall or partition. In order to fill the space between them, I make a box consisting of two movable sides, the studding forming the ends. These boards B are cut to a length which will admit them between the studding, so that their outer faces will be flush with the outer faces of the studding. Bars C extend across outside these boards, their ends resting upon the studding, as shown, and holes D are made through them to receive bolts E, by which the parts

are held in place. Strips F are nailed vertically upon the inside faces of the studding about midway between their outer faces. Iron stay-rods G extend between the studding, as shown, to hold them together and keep the filling in place. These parts being in place, the filling material is mixed in a liquid form or plastic condition, and is poured into the mold thus formed, where it is allowed to set until hard. The bolts E are then withdrawn, the bars C and boards B removed and replaced above the sections thus formed, and the process repeated until the whole space is filled. The bolts E are easily withdrawn, and without danger of breaking the filling material, which is held solidly in place by the stay-rods and strips F. By this method the filling is rapidly and cheaply introduced, there being no cartage of blocks, no breakage or waste of material, and no expense for skilled labor.

Having thus described my invention, what I claim as new, and desire to secure by Letters Patent, is—

1. The inclosure or mold consisting of the removable sides B, extending between the studding and held in place by the bars C, and the bolts E, passing through the sides and bars and uniting the parts, substantially as herein described.

2. The studding A, with the vertical projecting strips F on the inner faces, and the stay-rods G, uniting the studding so as to pass through the interposed filling material, substantially as herein described.

In witness whereof I have hereunto set my hand.

LEONARD E. CLAWSON.
